UNITED STATES PATENT OFFICE.

EDWIN A. TERKELSEN, OF BOSTON, MASSACHUSETTS, ASSIGNOR TO ANDREW TERKELSEN, OF NEWTON, MASSACHUSETTS.

MECHANICAL PRESS.

Application filed February 7, 1927. Serial No. 166,335.

This invention relates to presses for use in the die working of, and in analogous operations upon, materials of such a nature as to require their subjection to a constant pressure for a substantial time, during which volumetric changes take place in the materials themselves as a result of such pressure either with or without concurrent heat or other treatment. In the co-pending application 10 of Jasper Derry, Serial No. 7,190 filed February 5, 1925 a press suitable for this purpose is described in which press elements are relatively moved toward one another to exert any desired pressure upon work interposed 15 between them and in which a resilient follow-up pressure of like amount is thereafter automatically applied in response to volumetric changes in the work.

The present invention has for its chief object to provide a compact and wholly mechanical press of this type which is particularly adapted for use in heavy work and which may be readily and conveniently adjusted to adapt it for work of various sizes 25 and for applying and maintaining for a required interval any desired substantially constant pressure.

The foregoing and other objects of the invention, together with means whereby the latter may be carried into effect will be more clearly understood from the following description of one form or embodiment thereof illustrated in the accompanying drawings. It will be understood, however, that the 35 particular construction described and shown has been chosen for illustrative purposes merely and that the invention as defined by the claims hereunto appended may be otherwise embodied without departure from the scope and spirit thereof.

In the drawings:

Fig. 1 is a front elevational view of a press embodying the invention;

Fig. 2 is a side elevational view of the 45 same; and

Fig. 3 is a view taken along the line 3—3, Fig. 1.

The press, as shown, comprises a supporting base 10 in which upright posts 11 are mounted and secured thereto by nuts 12 engaging the lower threaded portion 13 of the posts, the lower side of the base 10 being provided with supporting legs 14. The upper side of the base is provided with upwardly projecting bosses 15 for positioning

relatively heavy springs 16, the upper ends of which are positioned around bosses 17 projecting downwardly from a cross-head 18 provided with openings for the posts 11. Nuts 20 are provided on a threaded portion 60 21 of the posts 11 for limiting the uppermost position of the cross-head 18 which is held thereagainst by the stress of the springs 16 which, in turn, are held under an initial compression thereby.

A lower movable press element or ram 25 is provided with openings adapted to engage posts 11 for guiding it in its upward movement. A double toggle is provided for moving the ram 25 comprising the upper 70 links 26 and lower links 27 pivotally mounted upon shafts 28. The links 27 are pivotally mounted at their lower ends upon shafts 29 in lugs 30 projecting upwardly from the cross-head 18, which constitutes an 75 abutment for the toggle, and the upper links 26 are pivotally mounted at their upper ends upon the shafts 31 in lugs 32 projecting downwardly from the ram 25. The shafts 28 are connected by links 33. A cam follower 80 34 is mounted upon one of the shafts 28 and spaced from the other by the links 33.

The upper press element or bed normally is adjusted to a stationary position. In the 85 press illustrated in the drawings, the bed 36 is provided with openings to receive the posts 11. A nut or collar 37 engaging the upper threaded portion 38 of each post 11 has secured thereto or formed integral therewith a worm gear 39. The clamp 40 arranged to engage the top of each gear 39, is adjustably secured to the bed 36 by an adjusting screw 41 engaging a threaded hole 42 in the bed 36. The head of the adjusting 90 screw 41 is provided with an operating hand wheel 43. In accordance with the invention means are provided for adjusting the normally stationary press element or bed relative to all its supporting members simultaneously. Thus, parallel shafts 44, each provided with gears, such as a worm 45, engaging the gears 39, are held in suitable bearings provided by brackets 46 secured to the bed 36 by bolts 47. The shafts 44 may 105 be suitably connected, and for this purpose one or both ends may be provided with a sprocket 48 connected by a chain 49. A hand lever 100 is provided upon the end of one of the shafts 44 for moving the gears 39 simul- 110

taneously and thereby adjust the position of the bed 36.

Side uprights 50 are connected with the base 10 by an angle bar 51 which is secured upon the uprights 50 and the base 10 by bolts 52. The uprights 50 are further reinforced by straps 53 and 54, the former being secured to the upper end of the posts 11 by bolts 55 and to the uprights 50 by bolts 56, the latter being secured to the uprights by bolts 57 and are provided with openings to receive the posts 11. A shelf 60 carrying a motor 61 extends between the uprights 50 and is secured to lugs 62 thereon. A shaft 65 mounted in suitable bearings in the uprights 50 is provided with a loose gear 66 meshing with a pinion 67 upon the armature shaft of the motor. Clutch mechanism generally indicated at 68, operated from the front of the press by a rod 69 pivotally mounted in a lug 70 in the side uprights 50, is adapted to connect the gear 66 with the shaft 65. A pinion 71 fast on the shaft 65 meshes with a gear 72 mounted upon a shaft 73 rotatable in suitable bearings in the side uprights 50. A pinion 74 is arranged upon a shaft 73 for engagement with a gear 75 upon a shaft 76 rotatably mounted in bearings in the uprights 50. A pinion 77 upon the shaft 76 is arranged for engagement with a gear 78 upon the main shaft 79 rotatably mounted in suitable bearings in the uprights 50. A cam 80 is mounted upon the shaft 79 so as to engage the cam follower 34 operatively connected with the toggle. The operative portion of the cam 80 comprises a relatively long and gradual rise between the points *a* and *b*, a dwell or concentric portion between the points *b* and *c* and a relatively quick fall between the points *c* and *a*.

In operation, the cam 80 is rotated in the direction of the arrow (Fig. 2) from the motor, or other suitable source of power supply, through the gear train and operates the toggle by engagement with the follower 34. It is customary in presses of this type, in order to insure smooth running and avoid possibility of overthrow, to straighten the toggle only approximately but not completely, the maximum force being exerted when the toggle is moved into its most nearly straightened condition. As the cam rotates in the direction indicated by the arrow in Fig. 2, the toggle is gradually straightened to move the ram 25 upwardly when the cam follower 34 engages the cam between points *a* and *b*, and is held in such position when the follower 34 is in contact with the cam between the points *b* and *c*. The collective strength of the springs 16, as determined by their initial compression by adjustment of the nuts 20, is sufficient to enable said springs to transmit without yielding forces materially less than the pressure to be ex-

erted by the press, but to cause them to yield when that pressure is approached. When, therefore, the toggle is straightened, the reaction thereof against the cross-head or abutment 18 causes the springs to yield and the cross-head to be depressed slightly out of engagement with the nuts 20. Thereafter, as the ram is held in its uppermost position, the clearance between the cross-head 18 and nuts 20 permits the springs 16 to exert a follow-up pressure upon the work as the latter contracts. When the work has been molded as desired, the movement of the cam 80, by contact of the cam follower 34 therewith between the points *c* and *a*, causes the toggle to be broken and the ram 25 to be withdrawn. It will be understood that the weight of the ram 25 is sufficient to maintain the follower 34 in contact with the cam 80 at all times.

The stress or initial compression of the springs 16, which controls the pressure the toggle exerts upon the work, may be conveniently adjusted to any predetermined desired amount by operating the press, under its own power, to straighten the toggle, thereby compressing the springs and disengaging the cross-head 18 from the nuts 20, as above explained, whereupon the press may be stopped with the toggle in this condition and the nuts 20 adjusted without effort. Thereafter the toggle may be broken to relieve the pressure of the ram on the bed, and the position of the latter readjusted in accordance with the adjustment of the nuts 20 and cross-head 18.

The position of the bed 36 may be adjusted quickly and uniformly relative to its supporting members or posts 11 by turning the wheel 43 operating the screw 41 to decrease the frictional engagement of the clamp 40 with the gears 39. The gears 39 are then actuated simultaneously to move the bed 36 either upwardly or downwardly depending upon the direction in which the handle 100 is turned. When the bed 36 is adjusted to the desired position, the clamp 40 again is brought into frictional engagement with the gears 39 by turning the wheel 43 on the screw 41.

The provisions of the invention are suitably and particularly adapted for a press of extremely large capacity because the pressure for operating the toggle is applied at a low point upon the press and the direction of this pressure approaches a downward pressure as the tension on the springs is increased by adjustment. By such provisions the stability of the press is assured under all operating conditions. Furthermore it will be noted that the press may be adapted and readily adjusted for the application of any desired pressure to the work being molded and the operative position of the press elements may be quickly and uni-

formly adjusted as required by the size of the work being molded.

What I claim is:

1. In a press, in combination, relatively movable press elements, a resiliently supported abutment, mechanism supported upon and reacting against said abutment for raising one of said elements to compress material therebetween with a desired pressure, adjustable means for controlling the uppermost position of the abutment, and means for operating said mechanism, said abutment being adjusted upon its resilient support to move out of contact with said adjustable controlling means when said mechanism is operated, whereby said abutment may rise in response to volumetric changes in said material to maintain a substantially constant pressure thereon. 70
2. In a press, in combination, relatively movable press elements, a spring supported abutment, a toggle supported upon the abutment for raising one of said elements to compress material therebetween, means for operating the toggle, and means for adjusting the position of the abutment against its spring support to limit its uppermost position, the arrangement being such that when the toggle is operated the abutment will move away from its uppermost position, whereby said spring support may operate in response to volumetric changes in said material to maintain the latter under a substantially constant pressure. 80
3. In a press, in combination, relatively movable press elements, an upright member for guiding said elements, a spring supported abutment guided by said member, mechanism supported upon the abutment for raising one of said elements to compress material therebetween with a desired pressure, a nut on said member above the abutment for limiting the uppermost position of the abutment, and means for operating said mechanism, the arrangement being such that when the mechanism is operated the abutment will move away from its uppermost position, whereby said spring may operate in response to volumetric changes in said material to maintain the latter under a substantially constant pressure. 90
4. In a press, the combination with a ram and means for operating the same, of a bed and an abutment supporting said operating means and against which the latter reacts, springs disposed beneath and supporting one of said last-named parts and acting to force the same toward the other, adjustable means for opposing the movement of said part by said springs whereby said springs are held under stress, and means for adjusting the position of the other of said parts. 100
5. In a press, the combination with a ram and a toggle for operating the same, of a bed and an abutment supporting said toggle and against which the latter reacts, springs disposed beneath and supporting one of said last-named parts and acting to force the same toward the other, adjustable means for opposing the movement of said part by said springs whereby said springs are held under stress, and means for adjusting the position of the other of said parts. 110
6. In a press, in combination, a bed, a ram, operating means for moving said ram toward said bed, an abutment supporting said operating means and against which the latter reacts, springs disposed beneath and supporting said abutment and acting to force the latter toward said bed, adjustable means for opposing the movement of said abutment by said springs whereby said springs are held under stress, and means for adjusting the position of said bed. 120
7. In a press, in combination, relatively movable press elements, a spring supported abutment, a toggle supported at one end upon the abutment and connected at the other end to one of said elements and having a cam follower connected therewith, and a cam mechanism arranged to engage the follower to operate the toggle and compress material between said elements, said abutment being adjustable upon its spring support to maintain said movable element against said material with a substantially constant desired pressure. 130
8. In a press, in combination, supporting members carrying relatively movable press elements, mechanism for raising one of the elements to compress material therebetween, means for operating said mechanism, a resilient member for actuating said element in response to volumetric changes in said material, and means for adjusting the other press element relative to all the supporting members simultaneously. 140
9. In a press, in combination, supporting members carrying relatively movable press elements, mechanism for raising one of the elements to compress material therebetween, means for operating said mechanism, a resilient member for actuating said element in response to volumetric changes in said material, and means for adjusting the other press element relative to all the supporting members simultaneously, and means for locking said other element in its adjusted position. 150
10. In a press, in combination, a base, a plurality of supporting members secured to the base and carrying movable and normally stationary press elements, and a mechanism for adjusting the position of the normally stationary press element relative to all the supporting members simultaneously. 160
11. In a press, in combination, a plurality of supporting members, movable and normally stationary press elements carried thereby, mechanism for adjusting the position of the normally stationary element rela- 170

- tive to all the supporting members simultaneously, and means for locking said element in its adjusted position.
12. In a press, in combination, threaded upright members carrying a press element, a nut on each upright member engaging the press element and provided with a gear, and means for actuating the gears simultaneously to move said press element.
- 10 13. In a press, in combination, threaded upright members carrying a press element, a nut on each upright member actuating the press element and provided with a gear, means for actuating the gears simultaneously to move said press element, and means for locking said element in its adjusted position.
- 15 14. In a press, in combination, threaded upright members carrying a press element, a nut on each upright member engaging the press element and provided with a gear, means for actuating the gears simultaneously to move the press element, and a clamp secured to said press element and adjustable to engage said gears.
- 20 15. In a press, in combination, threaded upright members carrying a press element, a nut on each upright member engaging the top portion of the press element and provided with a gear, means for actuating the gears simultaneously to move the press element, and a clamp above the press element secured thereto and adjustable to engage the top faces of said gears.
- 25 16. In a press, in combination, threaded upright members carrying a press element, a nut on each upright member engaging the top portion of the press element and provided with a gear, means for actuating the gears simultaneously to move the press element, and a clamp above the press element secured thereto and adjustable to engage the top faces of said gears.

In testimony whereof I affix my signature.

EDWIN A. TERKELSEN.
